TAPE DRIVE UNIT OR THE LIKE

Thomas Cecil Laughon, Rochester, N.Y., assignor to
Eastman Kodak Company, Rochester, N.Y.

Continuation-in-part of design application Ser. No.
338,702, Mar. 7, 1973. This application July 5,
1973, Ser. No. 376,769

Term of patent 14 years

Int. Cl. D14—02
U.S. Cl. D26—5 C

FIG. 1

FIG. 2

FIG. 3

FIG. 1 is a front perspective view of a tape drive unit showing one side, the front and top of my design;

FIG. 2 is another front perspective view of the tape drive unit of FIG. 1 taken from the opposite side of that shown in FIG. 1 wherein a door is shown in an open position; and

FIG. 3 is a rear perspective view of the tape drive unit of FIG. 1 showing one side, the back, and the bottom thereof.

This is a continuation-in-part of application Ser. No. 338,702, filed March 7, 1973.

I claim:

The ornamental design for a tape drive unit or the like, as shown.
